US00D862813S

(12) **United States Design Patent** (10) Patent No.: **US D862,813 S**
(45) Date of Patent: **** Oct. 8, 2019**

(54) **DOG TRAINING CLICKER**

(71) Applicant: **Zhi Heng Liu**, Mong Kok (HK)

(72) Inventor: **Zhi Heng Liu**, Mong Kok (HK)

(**) Term: **15 Years**

(21) Appl. No.: **29/640,803**

(22) Filed: **Mar. 16, 2018**

(51) LOC (12) Cl. **30-99**

(52) U.S. Cl.

USPC **D30/199**

CLAIM

The ornamental design for a dog training clicker, as shown.

DESCRIPTION

FIG. 1 is a front view of a dog training clicker showing my new design;

FIG. 2 is a rear view thereof;

FIG. 3 is a left view thereof;

FIG. 4 is a right view thereof;

FIG. 5 is an overhead view thereof;

FIG. 6 is an opposite overhead view thereof;

FIG. 7 is a front perspective view thereof; and,

FIG. 8 is a rear perspective view thereof.

1 Claim, 8 Drawing Sheets
